UNITED STATES PATENT OFFICE.

JOHN J. DUNLAP, OF CANTON, OHIO.

INCANDESCENT VAPOR-BURNER.

SPECIFICATION forming part of Letters Patent No. 660,528, dated October 23, 1900.

Application filed March 7, 1900. Serial No. 7,654. (No model.)

To all whom it may concern:

Be it known that I, JOHN J. DUNLAP, a citizen of the United States, residing at Canton, in the county of Stark and State of Ohio, have 5 invented certain new and useful Improvements in Incandescent Vapor-Burners; and I do hereby declare that the following is a full, clear, and exact description of the same, reference being had to the annexed drawings, 10 making a part of this specification, and to the figures of reference marked thereon, in which—

Figure 1 is a side elevation. Fig. 2 is a vertical section. Fig. 3 is a detached view 15 of the gas-tip, needle-chamber, and connecting section or part. Fig. 4 is a top view. Fig. 5 is a detached perspective view of the gas-tip and its parts. Fig. 6 is a transverse section on line $x-x$, Fig. 1, except the chimney-holder is shown removed. Fig. 7 is a top view 20 of the part shown in Fig. 5.

The present invention has relation to incandescent vapor-burners; and it consists in the different parts and combination of parts 25 hereinafter described, and particularly pointed out in the claim.

Similar numerals of reference indicate corresponding parts in all the figures of the drawings.

30 In the accompanying drawings, 1 represents the body, which is substantially of the form shown, and, as shown, it is provided with the vaporizing-passages 2 and 3, which passages are located substantially as shown, and, as 35 shown, they converge toward their upper ends and are united at the upper limit of said passages, and for the purpose of increasing the vaporization the upper portions of said passages are located through the bars 4, said bars 40 being formed integral with the body and are located within the chamber 5, as illustrated in Fig. 2. Upon the top or upper end of the chamber 5 is located the convexo-concave gauze disk 6, through which disk extends the 45 head 7, which head is located upon the joined portions of the bars 4 and is for the double purpose of providing a body of metal directly over the point where the passages 2 and 3 come together and above the point 50 where the fuel changes its upward flow to a downward flow.

By extending the head 7 through the gauze

disk 6 and a short distance beyond the top or upper side thereof the flame will be shunted toward the inner periphery of the mantle 8, 55 by which arrangement a better light is produced.

For the purpose of conveying the fuel to the gas-tip 9 the vertical pipe or tube 10 is provided and is connected at a point directly 60 below the bottom or lower end of the passage 3.

The bottom or lower portion of the pipe or tube 10 is provided with the horizontal portion 11, which horizontal portion 11 is provided 65 with the passage 12, said passage leading to the tip 9. Directly below the tip 9 is located the needle 12', which needle is for the purpose of regulating the flow of gas.

The feed-pipe 13 is connected to the body 70 1 in the ordinary manner and may be provided with a valve or cut-off 14, said valve or cut-off being particularly shown in Fig. 1.

For the purpose of surrounding the gas-tip 9 the housing 15 is provided, which housing 75 is supported in the usual manner.

Within the housing 15 is located a short tube 16, which tube forms a guide for the fuel after it has passed the tip 9.

For the purpose of preventing air from entering at the side of the housing at the place where said housing overlaps the pipe or tube 10 said pipe or tube is provided with the laterally-extended flanges 17. Said flanges are formed of a shape to correspond, substantially, with the form of the housing 15.

It will be understood that by locating the head 7 in the center of the gauze disk and directly over the vertical center of the cylinder the flame will be more equally distributed, by which arrangement the same volume of flame will be around the head, by which arrangement a more even and uniform light is produced.

The thimble 16' is located within the tube 95 or mixing-chamber 16 and is held in proper relative position by frictional contact.

The head 7 is located in the center of the gauze disk 6, a portion of said head being above the disk and a portion below the disk, 100 and is so located for the purpose of better heating the head, and at the same time by providing the convexo-concavedisk the flame is shunted toward the inner periphery of the

mantle. Another object and purpose of locating the head as described is to provide for turning the light down or, in other words, reducing the supply of fuel, and yet provide sufficient heat to maintain a small light and at the same time produce sufficient heat to generate or vaporize a sufficient amount of gas to maintain the light when turned down. Heretofore the light when reduced in volume would not produce sufficient heat to maintain the light when reduced.

Having fully described my invention, what I claim as new, and desire to secure by Letters Patent, is—

15 A body provided with a chamber at its upper end and having up and down passages formed in its lower portion, a convexo-concave gauze disk covering said chamber, bars

projecting inwardly across said chamber and having passages formed therein which continue the up and down passages in the body, and a head formed at the meeting of the bars and lying above and below the gauze disk, the passages in the bars being below said disk and head, a feed-pipe connected to the body and opening into the up-passage, a pipe connected to the down-passage and provided with a vapor-vent, and a needle-valve controlling such vent, substantially as set forth.

In testimony that I claim the above I have hereunto subscribed my name in the presence of two witnesses.

JOHN J. DUNLAP.
